UNITED STATES PATENT OFFICE

2,555,105

SAFETY RAZOR

Joseph Rene Ayotte, Chicago, Ill.

Application June 25, 1946, Serial No. 679,223

2 Claims. (Cl. 30—69)

1

This invention relates to improvements in razors of the so-called safety types, and more particularly, has reference to improvements in the type of safety razor construction described and claimed in my United States Letters Patent No. 2,348,590, dated May 9, 1944.

The invention has for an object to provide a razor in which adjustment between the guard and clamping plates thereof may be effected in a manner whereby a blade arranged between the same will have its cutting edge selectively and precisely adjusted and/or positioned and then secured with relation to the guard plate to afford advantageous, and at the same time, maximum shaving efficiencies, more especially, whereby the greatest possible results and shaving satisfaction will be attained when the razor is used to remove beards of heavy, light, soft, tough or other character.

A further object of the invention resides in the provision of a razor construction whereby, with visually guided precise, relative selective adjustment between the guard and clamping plates, a blade positioned or received therebetween will be bodily moved and then firmly secured against any and all possibility of relative movement, in contradistinction to being bodily flexed, and so, permitted to shave a surface with materially greater efficiency, comfort and satisfaction to the user.

Another salient feature of the invention is to provide the interengageable razor guard and clamping plates with means which will visually facilitate their predetermined relative angular adjustment to a fine degree and, in addition, serve to guide such plates during and throughout their movement of relative adjustment, hence, assuring proper assembled positioning of the same and the proper retention of an edge-adjusted blade by and between the same.

Yet another object of the invention is to provide a highly novel and advantageous form of connection between the guard and clamping plates and the razor handle, so constructed that flush and full bearing engagement will, at all times and irrespective of the degree of their relative angular adjustment or positioning, be effected between adjacent portions of the guard plate and the handle, thus providing for solidity and stability of the construction, and moreover, eliminating the existence of space or crevices between such parts, in which foreign matters might accumulate, and in so doing, materially detract from the cleanliness and sanitary features of the device.

The foregoing, as well as other objects, ad-

2

vantages and meritorious teachings of my invention, will be in part obvious and in part pointed out in the following detailed disclosure thereof, when taken in conjunction with the accompanying drawings, it being understood that the form of the invention presented herein is precise and what is now considered to be the best mode of embodying its principles, but that modifications and changes may be made in specific embodiments without departing from its essential features.

In the drawings:

Figure 1 is a side elevation of the improved razor, with a portion of the handle thereof broken away and shown in section.

Figure 2 is a rear side elevation of the interengaged parts of the razor, i. e., the guard and clamping plates and a portion of the handle.

Figure 3 is an elevation of the normally inner face side of the razor guard plate.

Figure 4 is a similar view of the normally inner face side of the clamping plate.

Figure 5 is an elevation of a form of blade advantageous for use in connection with my improved razor.

Figure 6 is a transverse section through the assembled blade holder construction, including the guard and clamping plates, and a fragment of the handle, in which the clamping plate has been adjusted to effect positioning of the blade between the same and the guard plate for cutting or shaving light or soft beards, and

Figure 7 is a like view, but wherein the blade is positioned between the guard and clamping plates of the razor, for cutting or shaving heavy or tough beards.

Referring in detail to the drawings, the invention comprises, in general, interengageable members in the form of a guard plate 1, a clamping plate 2 fixedly carrying, intermediately of its opposite ends, a substantially right-angularly disposed screw-threaded stud 3, and a handle 4 having a co-axially disposed internally screw-threaded opening 5 formed in and opening onto its normally inner end, adapted, with assembly of the guard and clamping plates, to have the screw-threaded stud 3 turned thereinto.

I find it advantageous to employ a shaving blade, such as indicated by the numeral 6, in the improved razor construction.

The guard plate 1, of substantially rectangular shape, has a straight edge guard or skin engaging bar 7 on one side thereof, whose outer face is transversely curved (see Figures 3 and 6) to cause its even and smooth engagement with sliding

movement over a bearded or hair-growing skin area. The surface curved bar 7, as will be observed on reference to Figure 6 of the drawings, is laterally offset from the guard plate 1 and said plate is longitudinally shouldered, as at 8, along and over the entire length of its normally inner face. The shoulder 8 is straight and is arranged in spaced and parallel relation to the bar 7 and has its surface slightly transversely curved or rounded, for a purpose hereinafter more fully described. The opposite and parallel side of the guard plate 1 is laterally offset throughout its length in a direction corresponding to that of the bar 7, as at 9, and has a right angularly shaped recess 10 formed therein medially of its opposite ends. Also, a medially located opening 11, of shape and size to permit free entrance and engagement therethrough of the clamping plate carried screw-threaded stud 3, is formed in the guard plate 1 in proximity to though transversely spaced from the guide way 10. A portion of the material from which said guard plate is constructed, adjacent and about the opening 11, is drawn or otherwise suitably formed to constitute an outwardly extending and surface curved or rounded flange or swivel-head element 12. The opening therethrough aligns with the opening 11 in the guard plate and is of a shape and size as will permit free passage of the screw-threaded stud 3 therethrough (see Figure 6), particularly, when the plates 1 and 2 are assembled in interengaged and operative relationship. Notched portions or angular pockets 13 are formed in the opposite ends of the guard plate 1 inwardly of the bar 7 in proximity to the ends of the shoulder 8, and receive therein the free portions of guide pins (hereinafter described) carried by the clamping plate 2.

The clamping plate 2 is of a shape similar to that of the guard plate 1, save that its width is somewhat less. Thus, when positioned adjacent the guard plate, in the manner shown in Figures 1, 2 and 6, the laterally offset bar portion 7 will be extended for a distance beyond the near side thereof, as is usual in razor blade holders of the herein concerned types, allowing the bar, alone, to have contact with a to-be-shaved surface, and also, baring the edge portion of the plate 6 positioned and secured therebetween, for an obvious purpose. It is to be also noted, at this point, that a portion of the clamping plate 2 overlies the guard plate provided longitudinal shoulder 8 throughout its entire length.

The normally inner face of the clamping plate 2 is, preferably, slightly transversely curved or dished, while its outer face may be transversely curved or convex. Consequently, with the blade 6 arranged longitudinally of the same adjacent its dished normally inner face, a spaced though firm bearing point contact between the two members (clamping plate and blade) will be effected, as is well shown in Figures 1 and 6 of the drawings.

Shaving blade engaging and guide fingers 14 are fixedly carried by and on the normally inner face of the clamping plate 2 near, though in spaced relation to its inner edge or side and at its opposite ends, and extend therefrom at substantially right angles. The positioning of said fingers is such that when the clamping plate 2 is operatively interengaged with the guard plate 1, they will enter into and through the aforesaid angular recesses 13 in the guard plate, and so, assist in preventing relative turning movement

between the assembled guard and clamping plates.

The basal portion of the screw stud 3, i. e., that portion adjacent its point of jointure with the clamping plate 2, is square or straight sided, as indicated at 15, and the innermost straight side is parallel to the inner edge or side of said clamping plate.

To effect angular adjustment of the guard plate 1 with relation to its companionate clamping plate 2, whereby the safety exposed cutting edge of the blade 6 can be precisely and selectively adjusted for attaining or providing different shaving efficiencies, a screw-threaded opening is formed in an intermediate portion of the clamping plate outwardly and transversely of its straight sided basal portion 15, and has an adjusting screw 16 turned thereinto and therethrough. The outer end of said screw is formed with a knurled or otherwise suitable type of head 17, capable of being conveniently and effectively engaged or gripped for turning in either direction.

A right angularly disposed and inwardly extending adjustment indicating finger 18 having straight and parallel sides, is integral with or otherwise fixed to the outer edge or side portion of the clamping plate 2, outwardly of and in proximity to the headed adjusting screw 16, in the manner shown in Figure 4 of the drawings. Its positioning on said plate is such that when the plate is engaged with the guard plate 1, with the guide fingers 14 received in the recesses 13 of the latter plate, said adjustment indicating finger will be snugly and slidably received in and through the guide way 10 in the guard plate 2. Markings, such as the letters H, M, and L, are presented on the outer face of the indicating finger 18, and by selectively aligning them, or any one of them, with an appropriate marking on an adjacent portion of the near edge of the guard plate 2, visual indication or noting of angular adjustment between the guard and the clamping plate may be determined and effected. Thus, by turning the adjusting screw 16 in the required direction and to the necessary extent, relative angular positioning of and between the guard and clamping plates for attaining a particularly desired edge adjustment of the blade 6 arranged therebetween, can be precisely attained, whereby to afford a particular shaving efficiency, i. e., a most advantageous and/or efficient positioning of the blade for shaving different characters of beard—light, heavy, soft, or tough.

It will be also understood and appreciated that the adjustment indicating finger 18, by reason of its snug and slidable engagement in and through the guide way 10 of the guard plate 1, will serve to prevent any and all possibility of material lateral or end wise shifting movement by and between the guard and clamping plates, respectively; it being borne in mind that the opposite sides of the adjustment indicating finger 18 are straight and relatively parallel, hence, that they will ensure a true transverse and straight path of travel or movement between the guard and clamping plates 1 and 2, respectively, with movement and ultimate assembling of said plates.

As heretofore stated, a type or form of shaving blade, such as shown in Figure 5 of the accompanying drawings and indicated by the numeral 6, is preferably employed in my improved razor. This blade consists of a substantially rectangular body sharpened along one of

its edges, as at 19, and having laterally extended and longitudinally aligned ears 20 on its opposite ends. An intermediate portion of the opposite side of the blade body, that is, that side opposite to the sharpened edge 19, is cut away or recessed, as at 21, and the inner side of such recessed portion is of bowed or arcuate formation, as indicated by the numeral 22.

In using this particular type of blade in my improved razor, it is to be understood that the guard and clamping plates 1 and 2, respectively, are disengaged. Thereupon, it is preferable that the clamping plate 2 shall be held with its normally inner face side uppermost and in a substantially horizontal plane so that the blade 6 can be conveniently laid on that portion of said normally inner face directly adjacent and between the hereinbefore described guide fingers 14 thereon, as shown in dotted lines in Figure 4 of the drawings. In such position, the laterally extended and longitudinally aligned ears 20 will be abuttingly engaged with adjacent portions of the fingers 14, while the arcuate or bowed portion 22 of the blade body recess 21 will abuttingly engage with the adjacent portion of the near straight side of the basal portion 15 of the screw-threaded stud 3. At this time, the guard plate 1 is engaged over the blade provided clamping plate 2, with its normally inner face adjacent the same, permitting the screw-threaded stud 3 to engage in and through the opening 11 in the guard plate 1. Concurrently, the guide fingers 14 and the adjustment indicating finger 18 on the clamping plate 2, are engaged in and through their respective receiving openings 13 and 10 in the guard plate 1. The handle 4 is now end-wise juxtaposed with relation to the end portion of the screw-threaded stud 3 extended through the opening 11, and hence, through the swivel head element 12 of the guard plate 1. Thereupon, the screw-threaded stud 3 is turned into engagement with the internally screw-threaded co-axial opening in the adjacent end of said handle 4. Prior to a full turning of the handle 4 to a position to effect binding or clamping engagement between the guard and clamping plates 1 and 2, respectively, the adjusting screw 16 is turned either inwardly or outwardly with relation to its clamping plate 2. During such turning of the adjusting screw 16, it will be observed, on reference to Figures 6 and 7 of the accompanying drawings, that the inner end of the screw will be so positioned with relation to the guard plate 1, that this plate may assume different angular positions or positions of relationship with respect to its companion plate 2, i. e., the clamping plate. The character or extent of this relative movement between the guard and clamping plates 1 and 2 will be visually indicated to a user of the razor by observing the markings H, M or L, on the face side of the adjustment indicating finger 18 and their particular registration or positioning with respect to the cooperating mark or marking on the near edge portion of the guard plate 1.

Because of the provision of the swivel-head element 12 on the guard plate 1 and its engagement in the cupped end portion 23 of the handle 4, it is of importance to note that a firm or stable connection between the interengageable members of the razor blade holder and the handle 4 will be ensured; moreover, that with any change of the angular positioning of the guard plate 1 with relation to the clamping plate 2, as shown in Figures 6 and 7 of the drawings, the

swivel-head element 12 will turn or rotate in the cupped portion 23 of the handle 4 to compensate for such change, and hence, will prevent the occurrence or presence of space or crevices as between the engaged handle and the guard plate 1, in which foreign matters may accumulate. Consequently, the sanitary characteristics of the improved razor construction will be materially enhanced.

The handle 4, as will be fully understood by workers skilled in this particular art, may be of shape and size different from that herein illustrated. I have found it preferable, in actual use of my improved construction, to provide the peripheral surface of the cylindrical handle 4 with relatively equi-spaced grooves or ways, generally indicated by the numeral 24, and to knurl intermediate portions of the handle, as at 25, to facilitate gripping of the same. Also, it is preferable that the handle 4 shall be of hollow cylindrical construction and that its normally outer end shall be closed by an appropriate cap, plug or other device, such as indicated by the numeral 26.

In concluding, attention is directed to the fact that when a user of the improved razor construction has once effected an adjustment for a particular shaving efficiency, as by turning the adjusting screw 16 to the required position with relation to the clamping plate 2, whereby to effect the desired engagement with the guard plate 1, the construction may be assembled and disassembled without further adjustment. This is to say, the original adjustment of the adjusting screw 16 will maintain, so that when the guard and clamping plates, with a shaving blade 6 secured therebetween, are reassembled, their relative positioning, as originally effected, will be repeated.

By reason of the shoulder 8 formed on the normally inner face of the guard plate 1, it will be understood and appreciated that an adjacent portion of the blade 6 secured between said plate 1 and the clamping plate 2, will be fulcrumingly engaged with said shoulder during relative angular adjustment between the plates 1 and 2 through turning of the adjusting screw 16; this being in a manner similar to the mode of operation of the construction described and claimed in my aforesaid United States Letters Patent No. 2,348,590, dated May 9, 1944.

I claim:

1. A razor, including opposed inner and outer plates, means on one of said plates engageable with the other plate for effecting variable angular adjustment therebetween, an angular plate adjustment indicating finger fixed to and adjacent the normally outer edge portion of said outer plate disposed at substantially right angles thereto adapted, with angular adjustment between the plates, to move across the adjacent edge of the inner plate whereby to indicate the extent of angular adjustment between the inner and outer plates; a screw-threaded stud connected to and extended from the outer plate movably engaged through and extended beyond the inner plate, and a handle endwise movably receiving the inner plate and having said stud threadedly engaged in and with the same.

2. A razor, including a blade guard plate, a blade clamping plate adjacent the guard plate, rockable bearing means on one side of the guard plate, a handle having a cupped inner end rockably receiving said bearing means therein, means on the clamping plate engaged with a portion of the guard plate for effecting variable adjustment between said plates, an angular plate adjustment

indicating finger mounted on one of said plates adjacent its normally outer edge portion and disposed at right angles to said plate movable transversely over and with relation to the corresponding edge of the other plate whereby to indicate the extent of angular adjustment between the guard and clamping plates, and a screw-threaded stud connected to and extending from the clamping plate movably engaged through the guard plate and the rockable bearing means and threadedly engaged in and with said handle.

JOSEPH RENE AYOTTE.
